UNITED STATES PATENT OFFICE.

JOSEPH KOMOROUS, OF CHICAGO, ILLINOIS, ASSIGNOR TO PARISIAN NOVELTY COMPANY, OF CHICAGO, ILLINOIS, A CORPORATION OF ILLINOIS.

STRUCTURE COMPRISING DISKS COVERED WITH FLEXIBLE MATERIAL.

1,228,219.

Specification of Letters Patent.

Patented May 29, 1917.

Original application filed October 24, 1916, Serial No. 127,350. Divided and this application filed April 6, 1917. Serial No. 160,268.

To all whom it may concern:

Be it known that I, JOSEPH KOMOROUS, a citizen of the United States, residing at 4249 Twenty-first Place, Chicago, in the county of Cook and State of Illinois, have invented a new and useful Improvement in Structures Comprising Disks Covered with Flexible Material, of which the following is a specification.

10 My invention relates, more particularly, to structures comprising flanged circular disks covered with flexible material, as for example, and more particularly, celluloid, which are crimped over circular members, 15 as for example disks, with the edges of the covering material turned back over the flanges and interposed between the latter and the edges of the said circular members, my invention having been devised for use, 20 more particularly, in coin-receptacles of a kind wherein a removable cover-section constructed as above described, is rotatable on the body portion of the receptacle, this application being a division of my co-pending 25 application for U. S. Letters Patent Serial Number 127350 filed October 24, 1916.

It has been found in practice particularly where celluloid is used as a covering material for the cover-sections, that oftentimes 30 the crimping of the parts of the cover-section to connect them together does not cause these parts to be sufficiently rigidly clamped together to prevent the celluloid-covered disk from rotating on the circular member, 35 in the rotating of the cover-section on the body of the receptacle, as for example to move the cover to a position for opening the receptacle, such relative rotation of these parts being very objectionable particularly 40 as the covering usually has a mark thereon which indicates the position to which the cover-sections should be rotated before the cover-section can be removed.

My object is to provide, by the employment 45 of novel, simple and inexpensive means, for the engaging of the inturned portions of the covering with the inner circular member in a manner which will prevent rotation of the covered disk upon the 50 inner circular member.

Referring to the accompanying drawings: Figure 1 is a view in vertical sectional

elevation of a coin-receptacle embodying my improvement.

Fig. 2 is a section taken at the line 2 on 55 Fig. 1 and viewed in the direction of the arrow.

Fig. 3 is a plan view of the inner side of 60 the removable cover-section of the receptacle; and

Fig. 4, a broken enlarged view like Fig. 3, but showing the flanged portion of the outer disk of the cover-section, and its covering, in section.

The particular construction of coin-receptacle shown and in connection with which I have chosen to illustrate my invention, but without intention of limiting it thereto, comprises a circular wall-section 5 and a bottom-section 6, these two sections forming the 70 body of the receptacle, a cover-section 7, and means for locking the cover-section to the body-section.

The bottom-section 6 is formed of a flanged outer disk 8 and an inner disk 9, 75 the outer disk being covered with celluloid or other suitable covering material indicated at 10, and crimped at its flange to the outwardly flaring lower edge portion of the wall 5.

The cover-section 7, generally stated, is formed of an inner disk 11 and an outer flanged disk 12 covered with celluloid, or other suitable covering material, as represented at 13, the edges of the covering material extending around the annular flange 14 of the disk 12 and being interposed between this flange and the peripheral edge of the disk 11, which latter is held to the disk 12, by the crimping of the flange 14 over the 90 member 11 as shown in Fig. 1.

The means shown for locking the cover-section to the body-section involves an inwardly-extending flange 15 on the upper edge of the wall 5 containing a series of 95 notches 16, a series of downwardly and radially projecting lugs 17 on the disk 11 adapted, when the cover 7 extends into one position on the body of the receptacle, to register with, and pass below the recesses 16 100 whereupon the cover-section may be rotated on the body-section to interlock the lugs 17 with the portions of the flange 15 between the recesses 16, and a series of spring fingers

18 adapted to enter notches 19 in the lugs 17 and releasably hold the cover-section and body-section against relative rotation to prevent registration of the lugs 17 with the 5 recesses 16.

It will be understood that the coin-receptacle illustrated and described presents a marked instance of a structure wherein it is desirable that the parts of 10 the cover-disk be prevented from rotating relative to each other. If such rotation occurs the operator instead of rotating the disk 11 relative to the body-section will merely rotate the covered disk 12 relative 15 to the disk 11 and this will prevent the relative movement of the cover-section 7 and the body-section of the receptacle to the proper position for disengaging the lugs 17 from the flange 15. Furthermore should 20 the covered disk 12 carry a mark which when moved into registration with a mark on the wall 5, indicates to the operator the position to which the cover-section 7 should be moved on the body-section to disengage 25 these parts, the relative rotation of the disks 11 and 12 would destroy the functioning of such mark.

According to my invention I provide in the peripheral edge of the circular member 30 11 a plurality of notches some of which are indicated at 20, these notches being preferably arranged at substantially equal distances about the member 11, and of any desired number preferably, in the case of 35 a coin-receptacle to be carried in the pocket of the user, 10 or 12. In the process of crimping the flanged portion of the disk 12 into engagement with the member 11, with the covering 13 interposed therebetween, to 40 the position shown in Fig. 1, the inner edge portions of the celluloid covering 13 bulge, as indicated at 21, into the notches 20 generally to the position as shown in Fig. 4 thus producing an interlock between the 45 covering 13 and the walls of these notches and operating to hold the parts of the cover-section 7 rigidly together to such a degree that in the manipulation of the device the parts of the cover-section will perform as 50 a unitary structure. It will be observed that by my invention the desired interlock of the covering 13 with the member 11 may be effected without requiring any extra operation in the formation of the cover-section, without weakening the structure 55 and without additional expense.

While I have illustrated and described

a particular embodiment of my invention, I do not wish to be understood as intending to limit it thereto as the same may be variously modified and altered without departing from the spirit of my invention, it being my intention to claim my invention as fully and completely as the prior state of the art will permit. 60 65

What I claim as new and desire to secure by Letters Patent is:—

1. A structure formed of a flanged disk having covering material extending over a face thereof and over its flange, and a circular member interlocked with said flange, with the said covering material interposed between said disk and member, said member containing a notch in its periphery into which the said covering material extends 70 and interlocks therewith for the purpose set forth. 75

2. A structure formed of a flanged disk having covering material extending over a face thereof and over its flange, and a circular member interlocked with said flange, with the said covering material interposed between said disk and member, said member containing notches in its periphery arranged thereabout in a series and into 80 85 which the said covering material extends and interlocks therewith, for the purpose set forth.

3. A receptacle formed of relatively-rotatable body and cover portions, said cover portion being formed of a flanged disk having covering material extending over a face thereof and over its flange, and a circular member interlocked with said flange, with the said covering material interposed between said disk and member, said member containing a notch in its periphery into which the said covering material extends 90 and interlocks therewith, for the purpose set forth. 95

4. A structure formed of an inner circular member containing a notch in its periphery, and an outer disk having a flange about its peripheral edge with covering material extending over a face of said disk 100 and over its flange, said flange being crimped into interlocking engagement with said circular member with said covering material interposed between said flange and the periphery of said circular member, and 105 the said covering material extending into said notch. 110

JOSEPH KOMOROUS.
